(57) **CLAIM**

The ornamental design for an ironing apparatus, as shown and described.

DESCRIPTION

FIG. 1 is a perspective view of an ironing apparatus showing my new design;

FIG. 2 is a front elevational view of the ironing apparatus of FIG. 1;

FIG. 3 is a back elevational view of the ironing apparatus of FIG. 1;

FIG. 4 is a right side elevational view of the ironing apparatus of FIG. 1;

FIG. 5 is a left side elevational view of the ironing apparatus of FIG. 1;

FIG. 6 is a top view of the ironing apparatus of FIG. 1; and,
FIG. 7 is a bottom view of the ironing apparatus of FIG. 1.
The broken lines shown in the figure drawings are included
for the purpose of illustration and form no part of the
claimed design.
